ADJUSTABLE WORK BOARD FOR ARMED CHAIRS

Martin M. Harles, St. Louis, Mo.

Application May 20, 1948, Serial No. 28,145

1 Claim. (Cl. 155—127)

1

This invention is an adjustable lap and work board, with attachments mounted at the ends of the board and at the underside thereof whereby the board may be adjustably positioned upon the arms of a chair, over the lap of the user, for supporting the board in convenient position for use.

The principal object of the invention is to provide a combined and adjustable lap and work board adapted both to fit closely to the body of the user as seated in an armed chair, and provided also with adjustable devices at the under side of the ends thereof, such as above referred to, for supporting the board upon the arms of the chair, in convenient position for use.

Another object of the invention is to provide a lap and work board of the kind referred to, the same comprising a board dimensioned to overlie the arms of an armed-chair and formed at its inner margin with an arcuate recess for fitting up to the waist of the user, said board being formed at its ends with transversely extended flat, shallow and elongated slideways, at the under side of said board, slide-shoes slidably mounted in said slideways, work-board supporting shoes pivoted at their inner ends to the inner ends of tilting arms attached transversely at the ends of the work board, and the said shoes being pivoted medially to the slide-shoes of the slideways formed in the ends of the board, and means for tilting up or lowering the outer ends of the said tilting arms, to suit the convenience of the user.

With the stated objects in view, together with such additional objects and advantages as may appear in the specification, attention is now directed to the accompanying drawing as illustrating a preferred embodiment of the invention, and wherein

Figure 1 is a frontal elevational view of an armed chair, showing the adjustable lap and work board as positioned upon the arms thereof.

Figure 2 is a side elevational view of the assembly shown in Figure 1.

Figure 3 is an under-side view on an enlarged scale, of the lap and work board, showing the adjustable attachments referred to as mounted at the under side of the board, at the ends thereof.

Figure 4 is a cross-sectional detail on the line 4—4 of Figure 3, and on an enlarged scale.

The adjustable lap and work board as constructed in accordance with this invention, is designed for use upon an armed chair 5, as conventionally formed with the legs 5a, seat 5b, back 5c and side arms 5d. The board itself includes a broad and suitably elongated lap-board

2

6, the same being formed with an arcuately outlined or semi-circular recess 6a cut centrally in through the inner side of the board and whereby the board is adapted to fit up closely to the body of the user as seated in the chair 5. Flat and shallow grooves or slide-ways 6b are formed and extended medially into the ends of the board at the under side thereof, these grooves or slide-ways being beveled down inwardly along their lateral margins as at 6c, and there being saw-slots 6d extended on down below the bottom of the slide-ways, for a purpose to be described. A pair of sheet-metal slide shoes 7 are formed with angularly inturned flanges along their lateral margins as at 7a, and are thereby adapted for slidably fitting into the slide-ways 6b and slots 6d of the board 5.

A pair of elongated work-board supporting shoes 8 are provided, the same being formed angular in cross section for providing vertically pendant webs or stop flanges 8a, and thus adapted for positioning longitudinally upon the arms 5d of the chair, with the webs or flanges 8a turned inwardly down alongside the inner vertical sides 20 of the chair arms, to serve as stops against their accidental displacement. A pair of work board supporting arms or tilting arms 9 are pivotally pinned at their inner ends to the inner sides of the vertical flanges 8a of the shoes 8 by means of bolts or pins 10 passed horizontally through the aligned inner ends of the elements 9 and 8, and thus the arms 9 are adapted for vertical angular movement or tilting. These tilting arms 9 are formed or provided at their outer ends with vertically pendant beaks 9a, the same being transversely and arcuately slotted as at 9b for receiving and passing the horizontally extended adjustment bolts 11 which are seated at their headed ends through the blocks 8b anchored atop the shoes 8 at their outer ends. The bolts 11 are provided with thumb nuts 11a, whereby the tilting arms 9 may be raised or tilted up as desired and thus locked by turning up the thumb nuts. Knobs or bosses 9c are similarly depended medially at the under sides of the tilting arms 9, and adjustment bolts 12 are passed vertically and freely up through these knobs and are rigidly anchored by welding or otherwise centrally and smoothly through the bottoms of the slide-shoes 7, as indicated at 12a. Thumb nuts 12b are mounted upon the projected and threaded lower ends of the bolts 12. By this arrangement as the slide shoes 7 are moved inward or outward in the slideways 6b of the board 6, for adjusting the attached shoes 8 and arms 9 to the

arms 5d of the chair 5, the shoes 7 may be releasably locked to any such adjusted position by merely turning up the thumb nuts 12b.

It is thought that from the foregoing specification the construction, use and operation of the adjustable lap and work board will be fully understood. In such use the work board may be readily adjusted upon the arms of a chair, over the lap of the user, and may be tilted up vertically as desired, conveniently for use for writing, reading, or for work of any kind.

And while I have here shown and described a specific form and embodiment of the invention, and specific structural features thereof, it is understood that the form and features as shown may be changed or modified as desired, within the scope of the claim.

I claim:

A work board for adjustably mounting upon the arms of a chair, the said board being formed medially at its ends with wide, flat, shallow, depressed and suitably elongated slide-ways extended into the board at the under side thereof and in longitudinal alignment with each other, the lateral margins of these slide-ways being 25

beveled inwardly and there being narrow saw-slots following the bevel of the margins of the slide-ways and extended further down into the board below the bottom of the shallow slide-ways, and a pair of flat sheet-metal slide-shoes rectangular in form and having their lateral margins bent angularly upward to provide flanges conforming to the angular bevel of the saw-slots of the lateral margins of the slide-ways and thereby slidably fitted into the said narrow saw-slots of the slide-ways of the board, and thus adapted for adjustably supporting chair arm engaging elements as mounted upon and depended from the said slide-shoes.
